UNITED STATES PATENT OFFICE.

HENRY FUEHRER, OF HAZLETON, PENNSYLVANIA.

COMBINED REINFORCE AND MOLD-SUPPORT FOR CONCRETE STRUCTURES.

1,126,190.

Specification of Letters Patent. Patented Jan. 26, 1915.

Application filed June 12, 1913. Serial No. 773,257.

To all whom it may concern:

Be it known that I, HENRY FUEHRER, a citizen of the United States, residing at Hazleton, in the county of Luzerne and State of Pennsylvania, have invented certain new and useful Improvements in Combined Reinforces and Mold-Supports for Concrete Structures; and I do declare the following to be a full, clear, and exact description of the invention, such as will enable others skilled in the art to which it appertains to make and use the same.

This invention relates to a combined reinforce and mold support for concrete structures.

The object of the invention is to provide means for cheaply and strongly constructing concrete or cement walls and by the use of which the cement worker can make his own mold or form.

Another object is to provide a device of this character in which no studs are necessary to brace the forms and in which a minimum quantity of lumber is required to construct it.

This invention also comprehends details of construction which, together with the features above specified, will be better understood by reference to the accompanying drawings, in which:—

Figure 1 represents a transverse vertical section of a cement wall embodying this invention and in which some of the mold boards have been removed showing the completed wall and others remaining in position during the setting of the cement; Fig. 2 is a front elevation of a wall embodying this improvement and showing some of the mold boards removed and others in operative position. Fig. 3 is a detail perspective view of a mold support constructed in accordance with this invention; Fig. 4 is a horizontal section showing a modified form of the invention; Fig. 5 is a detail perspective view of the combined anchor and mold support employed in the construction shown in Fig. 4. Fig. 6 is a detail perspective view of a slightly different form of mold support provided with means for supporting a mold to form an offset around the surface of the wall to be constructed.

In the embodiment of the invention shown in Figs. 1 and 2 a plurality of anchors 1 are employed for holding the molds or forms in operative position during the construction of the wall. Each of these

supports or anchors consists of a bar preferably composed of soft steel, such as is known as "band iron" and which is preferably about one inch wide by one-sixteenth of an inch thick, more or less, the length of said bar conforming to the thickness of the wall to be constructed and the molds to be used. Each of these devices comprises a body portion 2 with prongs at its opposite ends to engage the upper edges of the lower mold boards and the lower edges of the upper mold boards next above as is shown clearly in Fig. 1. The ends of the bar are sheared and each bent to form four prongs 3, 4, 5 and 6, the prongs 5 and 6 being spaced a suitable distance from the ends to span the edges of the mold boards to which the anchor is to be applied.

The prongs 3 and 4 at the terminal of each bar are preferably formed by shearing the bar in the center and bending one-half thereof laterally in one direction and the other half in the opposite direction in position to engage and hold the upper edge of one board and the lower edge of the adjacent board against outward movement.

The prongs 5 and 6 are formed by striking out tongues from opposite edges of the bar and bending one in one direction and the other in the opposite direction thereby forming the prongs which hold the mold boards from inward movement. The cutting of these tongues which form the prongs 5 and 6 forms a weakened shank or neck 7 for a purpose to be hereinafter described. Prongs 8 are also formed by striking out tongues from opposite edges of the bar at points spaced inward from the neck 7 and bending them inwardly to form pockets for 95 employed as is shown clearly in Fig. 1.

In the use of this improved anchor and mold support a layer of concrete or cement is first disposed in a concavity such as a ditch upon which the wall is to be erected. This layer is placed without forms and is accurately leveled, and the wall is erected thereon in the following manner: The anchors 1 are placed on this foundation sufficiently close, about two feet apart more or less, to engage the lower edge of the mold which may be of metal, wooden boards or boards lined with metal of any desired design. Then a sufficient number of anchors 110 are placed to span and engage the upper edge of the first board of the mold. When

this is done these mold boards 10 may be held perfectly plum by forcing blocks or boards 11 at intervals between the mold boards to force said boards tightly against the prongs 3 and 4. The molds so formed may be arranged in perfect alinement and is ready to receive the concrete or cement. The blocks or boards 11 between the mold boards 10 are removed as soon as the molds have been filled in with the concrete which will hold the mold boards in position without the use of any additional boards or blocks. When this first course of the wall has been completed the second boards of the mold are placed in position and the prongs 3 and 5 at the ends of the anchor will engage the opposite faces of the lower edges thereof and hold these boards in alinement with the boards below with which the prongs 4 and 6 are engaged. Similar anchors are then engaged with the upper edges of the unfilled boards of the mold with the prongs 4 and 6 thereof engaging the opposite faces of said upper edge and blocks 11 may be arranged between said boards to force them against the outer prongs of the anchors if it is found to be necessary and said boards are thereby held firm and ready to receive the second course of cement. After these boards have been filled the blocks 11 are removed as above described and other boards may be added in the same manner until the wall is of the desired height. When the lower courses have become sufficiently hard the mold boards may be removed therefrom and used again on the upper courses. To remove these mold boards the outer prongs 4 are bent outwardly; which may be done with any suitable tool, above the upper edges of the lower mold boards with which they are engaged and these boards 10 may then be easily withdrawn for use on succeeding courses, the withdrawal thereof also bending the prongs 3 of the anchor below, which engages the lower edge thereof, downwardly as is shown clearly in Fig. 1. After removing the mold boards 10 the outer portions of the anchors are twisted thereby breaking them off at the necks 7 which are disposed within the concrete wall not less than one-half inch from the outer face thereof. By forming these weakened necks the outer ends of the anchors may be readily broken by twisting them back and forth once or twice and when the protruding board supporting ends have been removed the recesses left in the outer face of the wall are pointed up or cemented over producing a perfectly smooth outer face and completely covering the anchor and thus preventing rust stains on the surface of the wall.

During the construction of the wall before the cement is filled into the molds if it is desired to strengthen the walls longitudi-

nally the rods 9 are disposed in the pockets formed by the inwardly bent tongues 8 and the cement is filled in over these rods as shown in Fig. 1.

When it is desired to form an offset 70 around the surface of the wall such as at the base thereof the anchor shown in Fig. 6 is employed and in which the prong 12 is cut and extended out longer than those of the other anchors so that when said 75 prong 12 is bent downwardly it will engage the outer face of the upper edge of the mold board and a corresponding anchor disposed at the lower edge of said mold board has the tongue 12 extended upwardly 80 to hold the board 10' in position to form the offset as is shown clearly in Fig. 1.

In the form shown in Figs. 4 and 5 a wall is shown constructed with concavities or spaces between one face thereof and the plastering 13. The boards 14 employed in forming the inner face of the wall shown in these figures are arranged vertically the entire height from floor to ceiling thereby forming a vertical joint between the mold board on the inside of the wall and horizontal joints in the mold boards forming the outer surface of the wall. (See 14 and 15 of Fig. 4). These mold boards 14 are preferably provided with wooden studs or bars 16 having nails 17 driven therein from the inside and cast in the concrete when poured to hold said studs in place and to which the lathing is attached on which the plaster walls 13 are mounted. The form of anchor employed in connection with this style of wall is shown in Fig. 5 in which one end thereof is constructed similarly to the anchor described and shown in Figs. 1 and 2, the other end of said anchor is twisted to dispose the prongs 3', 4', 5' and 6' laterally instead of vertically as in the other figures to adapt these prongs for engaging the vertical mold board 14. The twisting, however, is not confined to the neck but it may be done at any point desired.

I claim as my invention:

1. A combined reinforcing anchor and mold support for concrete structures comprising a metal bar of uniform width throughout sheared at its opposite ends to form longitudinally spaced pairs of mold board engaging prongs, one pair of prongs having projections on their inner edges whereby a weakened neck is formed which connects said prongs with the body of said anchor.

2. A combined reinforcing anchor and mold support for concrete structures comprising a metal bar sheared at its opposite ends to form outer and inner mold board engaging prongs, the inner prongs having projections on their inner edges forming a weakened neck which connects said ele-

ments with the body of said anchor, and tongues cut out from the side edges of said bar and bent inwardly to form reinforcing rod receiving pockets.

5 3. A combined reinforcing anchor and mold support for concrete structures comprising a metal bar provided at its opposite ends with longitudinally spaced mold board engaging elements, weakened necks con-
10 necting said elements with the body of said

bar, said bar being twisted to dispose the board engaging elements in a plane at right angles to those at the other end of the bar.

In testimony whereof I have hereunto set my hand in presence of two subscribing wit- 15 nesses.

HENRY FUEHRER.
